INNER TUB WASHER

Frank J. Hayes, Brooklyn, N. Y., assignor of twenty per cent to Saul M. Slomsky, Brooklyn, N. Y.

Application February 3, 1941, Serial No. 377,089

4 Claims. (Cl. 68—13)

This invention relates to new and useful improvements in an inner tub washer.

More particularly, the invention proposes in combination with a sink and tub, an agitator mounted in the tub to do washing, a disappearing wringer mounted across an open top pocket located between the tub and the sink, and a standard electric ironer mounted in a cabinet arranged around the sink and tub.

Still further, the invention contemplates that the entire washer be enclosed in a steel casement enameled to harmonize with the color scheme of a modern kitchen or furnished basement or other place. The invention proposes a certain construction of this steel casement which will become clear as this specification proceeds.

The dominating advantage of the invention resides in the fact that it takes the washing machine out of the portable field and places it as a permanent fixture in the home of the future. It is believed that this invention will open up a new field to the washing machine industry, closed before through lack of space.

Still further, the invention proposes the construction of an inner tub washer as briefly described which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an inner tub washer constructed in accordance with this invention.

Fig. 2 is a fragmentary enlarged transverse vertical sectional view of a portion of Fig. 1 showing particularly the tub and the mechanism immediately adjacent the tub.

Fig. 3 is a vertical sectional view taken on the line 3—3 of Fig. 2.

Fig. 4 is a plan view of Fig. 1.

Fig. 5 is a plan view of the transmission mechanism.

Fig. 6 is a fragmentary horizontal sectional view taken on the line 6—6 of Fig. 3.

Fig. 7 is a fragmentary enlarged vertical sectional view taken on the line 7—7 of Fig. 2.

Fig. 8 is a fragmentary enlarged detailed view of a portion of Fig. 1 showing particularly the control panel for the washer.

Fig. 9 is a fragmentary vertical sectional view taken on the line 9—9 of Fig. 8.

Fig. 10 is a schematic wiring diagram of the device.

5 The inner tub washer in accordance with this invention includes a combination sink and tub having a sink portion 10 at the left hand end and the tub portion 11 at the right hand end. The usual hot and cold water mixing fixtures 12 are mounted over the sink and tub portion in a manner so that the water may be let into either one, as desired. An agitator 13 is mounted in the tub for agitating water and clothes therein to wash the clothes.

10 Means is provided for driving the agitator 13. This means includes a vertical shaft 14 which is coaxially connected with the agitator 13 and which extends through the bottom of the tub 11. A gear 15 is mounted on the bottom end of the shaft 14. A suitable water-tight casing 16 is mounted upon and through the bottom of the tub 11 and encircles the shaft 14. The gear 15 is located to the bottom of the casing 16. The gear 15 meshes with a segmental gear 17 which is 15 pivotally supported by a pintle 18. The gear 17 has a rear portion 17a extending rearwards from the pintle 18, opposite to the teeth portion of the segmental gear 17.

20 A link 19 pivotally connects with said rear end 17a of the segmental gear and extends laterally over the top face of a horizontal rotatively mounted gear 20. A pintle 21 pivotally connects the end of the link 19 eccentrically with the gear 20. The worm pinion 22 meshes with the gear 20 25 and is mounted upon a drive shaft 23. This drive shaft is adapted to be connected with an electric motor not illustrated on the drawings except schematically in Fig. 10 by reference numeral 88. The arrangement is such that rotations of the drive shaft 23 will cause the gear 20 to rotate which will cause the link 19 to oscillate, oscillating the segmental gear 17 which indirectly causes the agitator 13 to oscillate. This motion agitates the water and clothes in the tub 11, and accomplishes the cleaning and washing.

25 The combination sink and tub is hung upon a wall located to the rear thereof, and in addition is maintained in a horizontal plane by a plurality of legs 25 formed of angular material in cross-section. These legs extend from the bottom of the combination sink and tub to the floor. A cabinet 26 of stainless steel is built around the bottom portion of the combination sink and tub and covers the legs 25 and all of the members 30 located beneath the sink and tub. This cabi-

net 26 is provided with a door 27 directly to the front of the tub 11 to give access to the agitator driving means. It is also provided with a door 28 directly to the front of the sink 10 to give access to the ironer located beneath the sink and which will be hereinafter more fully described.

Adjacent the top and bottom corners to the right of the door 28 there is provided a superimposed pair of complementary tracks 29, and when the door is pivoted to an open position it is to be slid into an inoperative position on the tracks 29 beneath the sink 10. When the tub 11 is not in use the usual cover or drain plate 31 is mounted across the sides of the tub. This cover is capable of draining water and holding dishes as is customary.

The mechanism which has been described for operating the agitator 13 is positioned within a waterproof container or casing 30 mounted upon a wooden platform 30^a in turn positioned upon rubber strips 30^b. The rubber strips 30^b are in turn mounted upon cross bars 30^c mounted between certain of the legs 25 supporting the combination sink and tub. The rubber strips 30^b are provided for acting as shock absorbers for preventing the entire tub and sink from vibrating when the device is set in motion.

The folding and disappearing wringer is mounted across an open top face pocket 32 and in the form of a box is positioned between the tub and the sink. This wringer includes a frame consisting of a pair of end frame sections 33, see Fig. 6, which are joined together with a bridging section 34. The end frame sections 33 are vertically slidably engaged into the ends of the box forming the pocket. The arrangement is such that the wringer frame is capable of moving vertically.

As shown in full lines in Figs. 2 and 3, the wringer is in its lowermost position. A pair of superimposed rollers 36 are mounted across the end frame sections 33 and comprise the wringer proper, that is, the rollers between which the wash engages. The bottom roller 36 is resiliently supported by springs 37 which urge it upwards against the top roller 36. The top roller 36 is mounted on a shaft 38 which has one end passing through one of the end frame sections 33. The other end of this shaft is provided with the gear 39 which meshes with a gear 40 mounted on the shaft of the bottom roller 36. The arrangement is such that when the shaft 38 is driven, rotations will be transmitted by the gears 39 and 40 to turn the rollers 36 towards each other so that the clothes may pass between.

The shaft 38 extends into a transmission housing 42 at the near side of the pocket 32. A bevel gear 43 is mounted on the shaft 38 within the housing 42, and meshes with a bevel gear 44 mounted upon a vertical shaft 45 which extends out from the bottom of the housing. This vertical shaft 45 is telescopically connected with a tubular shaft 46.

The interengaging ends of the solid shaft 45 and the tubular shaft 46 are slidably but non-rotatively connected with each other. This is accomplished by the fact that they are square in transverse cross-section, see Fig. 5. They may be of any other non-circular shape. The tubular shaft 46 is turnably supported at its bottom end on the block 27'. Near its bottom end it is provided with a gear 48 which meshes with a rotatively supported gear 49. This latter gear 49 is also mounted on the block 27'. The gear 49 meshes with another gear 50 which is coaxially

connected with the gear 20. In this way rotations from the drive shaft 23 will be transmitted to rotate the drive system just described causing rotations of the shaft 38, and thus the operation of the wringer.

The bridging section 34 of the wringer frame supports a handle 51 of elongated shape. This handle is so located that the top of the bridge section 34 may be conveniently gripped and the fingers will then extend into the handle 51. The handle 51 is slidably mounted in an opening 52 formed in the bridging section 34. A rod 53 connects with one end of the handle 51 and extends through a portion of the bridging section 34. A spring 54 is coaxially mounted on the rod 53 and has one end 54^a connected with the rod and the other end 54^b attached on the bridging section 34. This spring functions to resiliently urge the rod 53 towards the right, in relation to Fig. 3, so that the handle 51 is moved to the right.

The other side of the handle 51 is provided with a rod 55 which extends through the bridging section 34 and into the end frame section 33 which is on the right. This rod 55 has a downwardly extending portion 55^a which extends to near the bottom end of the said end frame section 33. The section 55^a then continues into an outwardly extended end portion 55^b which engages against a rack 57 mounted on a portion of the combination sink and tub. This rack 57 extends to near the top of the pocket. The spring 54 functions to hold the outwardly extending end portion 55^b engaged with the rack.

When it is desired to extend the wringer into operative position, the top of the bridging section 34 is gripped so that the fingers engage the handle 51 which is then moved to the left, with specific relation to Fig. 3. This moves the rod 55 to the left so that the outwardly extending end portion 55^b disengages from the rack 57. Then the wringer may be lifted up to the position indicated by the dot and dash lines in Fig. 3. The handle 51 is now released and the spring 54 will move the handle 51 towards the right, moving the rod 55 in the same direction, so that the outwardly extending end portion 55^b engages the rack 57 holding the wringer in its raised position. It should be understood that the outwardly extending end portion 55^b is now engaging the top portion of the rack 57. When the wringer is extended to its raised position the telescopic shaft 45, 46 merely becomes extended. However, rotations will be transmitted by the telescopic shaft to drive the wringer rollers 36.

The rear wall on the tub 11 is formed with full tub water line overflow opening and outlet 59 which is connected with the sewerage, not illustrated on the drawings. Immediately adjacent the overflow opening 59, the rear wall of the tub has a small outwardly projecting compartment 60. This compartment is adapted for holding cakes of blue 61.

A hingedly mounted door 62 of porous material, such as wire mesh, extends across the compartment 60. Mounted across the porous door 62, there is a waterproof door 63. This waterproof door 63 is slidably mounted in a pair of parallel tracks 64 mounted on the rear wall of the tub 11. A rod 65 connects with the door 63 and extends upwards through a bearing 66. The top end of the rod 65 is provided with a ring 67 which may be manually gripped so that the door 63 may be moved to an elevated open position. The door 63 can be closed when desired. When the door 63

is opened, the porous door 62 may be opened to refill the bluing compartment 60.

A standard electric ironer is mounted in the base cabinet 26 directly behind the door 28. This ironer is so constructed that the door 28 may be opened and the ironer may be extended so that it is ready to be used. The ironer includes a table 70 which is supported on an L shaped arm 71. A brace 72 is extended between the legs 25 supporting the left-hand side of the sink 10, and carries a lug 72a. The L shaped arm 71 has one of its ends pivotally attached to the lug 72a by means of a pin so as to be capable of swinging in a horizontal plane. This horizontal swinging causes the ironer to be extended from beneath the sink when the door 28 is opened. The bottom face of the table 70 is provided with a lug 70a which is pivotally connected to the free end of the L shaped arm 71. The pivotal connecting between the L shaped arm 71 and the lug 70a is such that the table 70 is capable of being swung vertically upwards to an operative horizontal position. The table 70 is provided with hingedly mounted side leaf 75 which may be spread out when the table 70 is extended. A leg 76 is connected with the front end of the table 70. The motor driven roller 78 of the electric ironer is mounted on the table 70. The usual electric heated cover 79 is also supported on the table 70. Fig. 4 shows the electric ironer in its folded position.

The electric ironer may be used by first opening the door 28 and then pivoting the ironer first outwards and then upwards. When the table 70 reaches a horizontal extended position, the leg 76 is pivoted to a vertical position and rests on the floor to support the ironer. The leaves 75 are then opened up and held in extended positions in the usual way, details of which are not shown on the drawings since they form no part of this invention.

Located above the tub 11 there is a panel 80 having certain controlled mechanism for the washer. There is a time switch 81 controlled by a knob 81a and which may set to time intervals varying from one minute to fifteen minutes. The panel board 80 is also provided with a green light 82, a red light 83 and two manually operable switches 84 and 85. These parts are connected up in an electric current as illustrated in Fig. 10.

The circuit in Fig. 10 includes an electric plug 86 which may be plugged into the usual wall socket in the home, or other place. From the plug 86 there is a circuit 87 connecting the green light 82 and the time switch 81 in parallel and connecting the time switch 81 and the electric motor 88 in series. This circuit is provided with the switch 84 to control it. The motor 88 schematically illustrates the motor which is intended to drive the drive shaft 23. When the switch 84 is closed the green light 82 will be turned on and current will flow through the time switch 81 and when the time switch 81 closes through the motor 88, there is another circuit 90 connecting the green light 82, the red light 83, and the motor 88 in series. This circuit 90 is controlled by the switches 84 and 85. With this arrangement the time switch 81 may be turned off and then the switches 84 and 85 may be turned on to place the motor 88 in continuous operation. In this latter condition both the green light 82 and the red light 83 will be on.

The tub 11 is provided with the usual valve controlled drain 11a to the sewerage system.

The operation of the inner tub washer is as follows:

Fig. 1 shows the inner tub washer as it appears when not in use. Now the sink 10 may be used as desired. To use the washer the drain plate 31 is removed, then the tub 11 is filled with the clothes, water and soap as is required to wash the clothes. The agitator 13 is then set into operation. This is accomplished by proper control 10 of the time switch 81 and the switches 84 and 85. After a suitable time has passed the wringer is lifted up from its inoperative position, shown by the full lines in Fig. 3 to its operative position, indicated by the dot and dash lines in this figure. 15 The clothes are now passed through the wringer and stored temporarily in the sink 10. Then the tub 11 is drained through the valve controlled drain 11a.

The tub is then filled to the full tub line, as 20 controlled by the drain 59. The clothes are placed into the tub and the agitator 13 is set into motion to take any remaining soap or cleanser from the clothes. During this operation the water is permitted to run so that it is overflowing through 25 the opening 59. This washes away all soap and other substances which floats up to the surface of the water. The operation is continued until the clothes have thoroughly rinsed.

The clothes are then passed through the 30 wringer again and stored temporarily in the sink 11. The electric ironer is now extended into its operation position. The clothes are now passed through the ironer and the washing operation is completed.

35 While I have illustrated and described the preferred embodiments of my invention, it is to be understood that I do not limit myself to the precise constructions herein disclosed and the right is reserved to all changes and modifications coming 40 within the scope of the invention as defined in the appended claims.

Having thus described my invention, what I claim as new, and desire to secure by United States Letters Patent is:

45 1. A tub washer having a pocket slidably housing a wringer to be movable to an operative position extended from the top of said pocket, a rack mounted along one side of said pocket, a rod slidably mounted on said wringer, means urging said rod into a position in which one end of said rod engages said rack holding said wringer against being moved, and means mounted on said rod, whereby said rod may be manually moved against said first-mentioned means to disengage said rod from said rack freeing said wringer to be moved either up or down.

50 2. A tub washer having a combination sink and tub with a pocket disposed between said tub and sink and slidably housing a wringer to be movable to an operative position extended from the top of said pocket, a rack mounted along one side of said pocket, a rod slidably mounted on said wringer, means urging said rod into a position in which one end of said rod engages said rack holding said wringer against being moved, and means mounted on said rod, whereby said rod may be manually moved against said first-mentioned means to disengage said rod from 55 said rack freeing said wringer to be moved either up or down, said first means comprising an expansion spring coaxially mounted on a portion of said rod and having one end connected with said rod and one end connected to a stationary portion of said wringer for urging said rod into an

extended position in which its end adjacent said rack engages said rack.

3. A tub washer having a combination sink and tub with a pocket disposed between said tub and sink and slidably housing a wringer to be movable to an operative position extended from the top of said pocket, a rack mounted along one side of said pocket, a rod slidably mounted on said wringer, means urging said rod into a position in which one end of said rod engages said rack holding said wringer against being moved, and means mounted on said rod, whereby said rod may be manually moved against said first-mentioned means to disengage said rod from said rack freeing said wringer to be moved either up or down, said first means comprising an expansion spring coaxially mounted on a portion of said rod and having one end connected with said rod and one end connected to a stationary portion of said wringer for urging said rod into an extended position in which its end adjacent said rack engages said rack, said latter means com-

prising a handle fixedly mounted on a portion of said rod and slidably disposed within a complementary opening formed in a stationary portion of said wringer.

5. 4. A tub washer having a pocket slidably housing a wringer to be movable to an operative position extended from the top of said pocket, a rack mounted in said pocket and adjacent one end of said wringer, a rod slidably mounted on the top portion of said wringer and having one end engageable with said rack, a spring urging said rod into a position in which said one end engages said rack, a handle on said rod facilitating the manual movement of said rod against the action of said spring to disengage said rod from said rack freeing said wringer to be moved, said rod having its free end bent downwardly to extend into said pocket to be able both to engage the lower portion of said rack and to engage other portion of said rack in all extended positions of said wringer relative to said pocket.

FRANK J. HAYES.
